US00D976561S

(12) **United States Design Patent** (10) **Patent No.:** **US D976,561 S**
(45) **Date of Patent:** **** Jan. 31, 2023**

(54) **SHOE**

(71) Applicant: **NIKE, Inc.**, Beaverton, OR (US)

(72) Inventors: **Kyle D. Schenone**, Beaverton, OR (US); **Alexandra K. Ulmer**, Portland, OR (US)

(73) Assignee: **NIKE, Inc.**, Beaverton, OR (US)

(**) Term: **15 Years**

(21) Appl. No.: **29/818,823**

(22) Filed: **Dec. 10, 2021**

(51) LOC (14) Cl. **02-04**

(52) U.S. Cl.

USPC **D2/972**

(58) **Field of Classification Search**

USPC D2/896, 900, 902, 904, 906–908, 910, D2/915–924, 925–945, 969–979
CPC A43B 1/00; A43B 1/02; A43B 1/04; A43B 3/00; A43B 3/02; A43B 3/06; A43B 3/10; A43B 3/12; A43B 3/14; A43B 5/00; A43B 5/001; A43B 5/002; A43B 5/008; A43B 5/06; A43B 5/10; A43B 5/12; A43B 23/00; A43B 23/02; A43B 23/04

(57) **CLAIM**

The ornamental design for a shoe, as shown and described.

DESCRIPTION

FIG. 1 is a front perspective view of a shoe showing our new design;

FIG. 2 is a side view thereof;

FIG. 3 is an opposite side view thereof;

FIG. 4 is an opposite side front perspective view thereof;

FIG. 5 is a front view thereof; and,

FIG. 6 is a top view thereof.

The broken lines immediately adjacent to the shaded area define the bounds of the claimed design and form no part thereof. The broken lines depicting the remainder of the shoe form no part of the claimed design.

1 Claim, 6 Drawing Sheets
